UNITED STATES PATENT OFFICE.

JOHN FREDERICK MAKOWSKI, OF SAN FRANCISCO, CALIFORNIA, ASSIGNOR TO A. EVERETT BALL AND C. G. HIGGINS, BOTH OF SAN FRANCISCO, CALIFORNIA.

SAND-MOVING MACHINE.

1,100,897.

Specification of Letters Patent. Patented June 23, 1914.

Application filed November 26, 1912. Serial No. 733,608.

To all whom it may concern:

Be it known that I, JOHN FREDERICK MAKOWSKI, a citizen of the United States, residing in the city and county of San Francisco, State of California, have invented a new and useful Improvement in Sand-Moving Machines, of which the following is a specification.

My invention relates to sand moving machines, and has for its object to provide in machines of the character specified new and improved means for digging away sand accumulated in sandhills, and loading it on cars.

With the aforesaid object in view my invention consists in new and improved means for loosening the sand and causing it to move toward a given point; for lifting the sand by scoops from said point along an upwardly inclined box to a point over the cars, and for dropping the sand so lifted into the cars.

It also consists in the novel parts, combinations, and arrangements set forth in the following description, particularly pointed out in the claims, and illustrated in the accompanying drawing.

The drawing shows a side elevation of my machine.

Referring to the drawing, my machine consists of a frame 1, mounted on trucks 2, and a rail 3, which runs parallel with the slope to be attacked, whereby the machine may be shifted along the line of the slope back and forth, and made to approach the gradually receding face of the hill by "throwing the track" nearer the same.

A motor 4, of suitable character is located in the frame, and is operatively connected with the main shaft 5, on which a sprocket 6, is located.

Fixed to the frame and extending to near the level of the ground is a box 7, which rises to a point on the frame above the cars 45 to be loaded, and has an extension 8, outwardly therefrom and over the cars, provided with an open bottom 9, through which the sand falls into the cars.

An endless chain 10, is provided with 50 plates or, scoops 11, of a size adapted to pass readily through the box, entering at the bottom and passing through a hole 12, in the top, and so arranged as to throw the sand brought to the top into the extension 8, and

allow it to fall into the cars. The chain 55 passes over the sprocket 6, and over idle sprockets 13, 14, and 15. Sprocket 13, is pivoted in a guide block 16, and has a counterbalancing weight 17, which automatically takes up the variations of slack in the chain 60 10, which arise in the operation of the machine. Sprocket 14, is pivoted at the end of a boom 18, which is hinged to box 7, near its lowest extremity, and which may be moved about said hinge in a vertical plane. 65 Sprocket 15, is located at a point near the lowest extremity of the box, and acts so as to guide the chain into the box.

An auxiliary digging device 19, is located at the far end of the boom on the shaft 70 of the sprocket 14, consisting of blades adapted to be rotated by said shaft, and to loosen the sand in the vicinity of sprocket 14, so the scoops can readily draw it to the box 7. The device 19, saves the labor of 75 several shovels, and helps to bring the sand to the desired position by causing rapid caving as the supporting parts of the sandhill are drawn away.

The chain driven by sprocket 6, carries 80 the scoops over sprocket 13, and pulls the sand along from the end of the boom 18, to the lower opening of the box 7. There it is drawn into the box 7, and pushed along the bottom thereof to the extension 8, where it 85 drops into the car 20.

The arrangement for drawing the sand into a box and pushing it upward by plates or scoops, gives greater flexibility than can be obtained by buckets, a smaller motor being available for operating the machine, and smaller plates or scoops being usable. 90 A switch track 21, parallels track 3, and the cars are run thereon.

Having described my invention what I 95 claim as new and desire to secure by Letters Patent of the United States, modifications within the scope of the claims being expressly reserved is:

1. In a device of the character specified a 100 frame, a box extending diagonally from a point near the ground level to a point over the cars to be loaded, having an opening above said cars, a boom hinged to the lower end of said box movable in a vertical plane, 105 a boom sprocket located near the outer extremity of said boom, a box sprocket located near the bottom of the box, a driving

2
sprocket, a guideblock having a sprocket and a counterbalancing weight, other sprockets on said frame, and an endless chain passing around said sprockets provided with plates 5 of a size adapted to pass through the box.

2. In an excavator, a car, a supporting frame extending above the car, an inclined chute extending across the car, an endless carrier having flights extending into the 10 chute, a driving wheel on said frame at the upper end of said chute around which the carrier passes, a pivoted link at the bottom of said chute, a wheel at the bottom of

the chute, a wheel carried by the link, another wheel at the top of the frame, said 15 carrier passing around all of said wheels, a counter-weight connected with the upper wheel to keep the carrier under tension, and means to operate the carrier.

In testimony whereof I have hereunto signed my name in the presence of two witnesses this 11th day of November 1912.

JOHN FREDERICK MAKOWSKI.
